UNITED STATES PATENT OFFICE

2,518,095

COIN CONTROLLED VENDING MACHINE

Milton C. Taylor, Chicago, Ill., assignor to The
Bastian-Blessing Company, Chicago, Ill., a cor-
poration of Illinois

Application December 16, 1944, Serial No. 568,474

4 Claims. (Cl. 194—1)

1

The present invention relates to a check controlled dispenser or vending machine and more particularly a device for vending packaged merchandise when a predetermined price in one or more coins is deposited as the purchase price in the device.

Although the present invention can be used for self-powered as well as for manually operated dispensers, it is preferably constructed for hand powered dispensers whereby the coin transaction is taken care of upon the forward stroke of a manually reciprocated mechanism and the dispensing of the packaged article is accomplished upon the back stroke of the mechanism.

A further important object of the invention is to provide a coin controlled mechanism which can be readily changed in the field to function with various combinations of coins including pennies, nickels and dimes in various combinations so that price changes can be incorporated immediately in a few seconds and without altering the fundamental organization of the parts.

Another object of the invention is to provide a coin controlled mechanism which can be set and reset readily at will to take any number of coins of the same denomination to make up odd prices where one or more than one coin of the one denomination may be required with or without a coin of another denomination for such prices.

Another important object of the invention is the provision for the ready changing of interchangeable coin handling devices in event of service problems and the ready resetting of the coin metering elements already present in the machine in event of price changes; or a change in the package dispensed; or a shuffling of the coin handling devices for use in other machines.

A further object of the invention is to provide a scavenging coin return which is automatic in event insufficient coins are deposited for one purchase or excessive coins are left over after the one purchase which are insufficient for a second purchase, the scavenging operating to clear all coin handling elements whether the insufficiency is due to slugs or coins retained any place in the detecting device.

It is an object of the invention also to provide a mechanism which closely follows the legal concept of a purchase and sale by hand in that the authenticity of the tokens used in making the purchase is determined; then the amount of tokens is checked and if the amount is insufficient to make up the purchase price, the tokens are returned immediately so that there is no question

2

as to the adequacy of the consideration being determined immediately when the so-called request for delivery is made as when the manual control is operated upon its forward stroke.

5 Thereafter the moment the coins are accepted, an article has to be delivered before the machine returns to its ready position for the next purchase. The manual control is prevented from recycling itself or losing its control to deliver a package until its full reverse movement which delivers the article is accomplished.

A further object of the invention is to provide controls for various sized coins which are interchangeable in a main assembly and made up of 15 a major portion of parts that are identical to reduce inventory and repair supplies carried on hand by service stations.

A further object of the invention is to provide a coin controlled dispenser which is simple to manufacture, use and maintain, easy to operate and comparatively inexpensive to produce and repair.

These being among the objects of the present invention other and further objects will appear from the drawings, the description relating thereto and the appended claims:

Fig. 1 is a front elevational view of a packaged goods dispenser embodying the preferred form of the invention;

Fig. 2 is a horizontal section taken through 30 the dispenser shown in Fig. 1 illustrating the location of packaged goods on a rotary manually driven dispensing drum;

Fig. 3 is an enlarged perspective view of the working parts and elements embodying the preferred form of the coin control for obtaining manual actuation of the dispensing drum;

Fig. 4 is an enlarged plan view of a simplified coin control for handling one or more coins;

Fig. 5 is a side elevation of the elements shown 40 in Fig. 4;

Fig. 6 is a perspective view of a removable coin handling device forming a part of the invention;

Fig. 7 is a side elevation of the device illustrated in Fig. 5;

Fig. 8 is an edgewise view of the device shown 45 in Fig. 6 taken from the side thereof; and

Fig. 9 is a diagrammatic view of an arrangement by which coins of more than two denominations can be handled.

Throughout the several views like letters refer to like assemblies and like numerals refer to like parts or elements.

The organization of the embodiment illustrated is such that for the purposes of describing it, it can be divided into sub-assemblies,

namely, the article storage and delivery arrangement A, the manual drive assembly B, the coin detector C, the coin handling unit D, the scavenger E operable when the correct price has not been deposited, the coin accepter F operable when the correct purchase price has been deposited, and the transmission mechanism G interconnecting the drum and manual drive for operation when the correct purchase price has been disposed.

Article storage and delivery

The arrangement for storing and dispensing articles, such as the bottles 10 shown in Fig. 2, is the device disclosed and described in the application, Serial No. 549,146, filed by W. S. Conneil, B. F. Boettcher and C. M. Holmen, August 12, 1944, now Patent No. 2,435,177, dated January 27, 1948, reference to which is hereby made.

The bottles 10 are stacked in vertical rows as held in place by channel members 11 carried on a drum 12. The bottles in the rows are arranged at an angle of approximately 35° to the horizontal so that they can slip one by one from the bottom of each stack as the drum is rotated to index the stacks, one after another, over a delivery opening as at 13 into and through which the bottom bottle of each stack is dropped when released from the stack.

The storage drum 12 is pivoted for rotation on a shaft 14 and is provided with a gear wheel 15 in mesh with the spur gear 16 driven through a sprocket chain 17 from a sprocket wheel 18. Rotation of the drum takes place in a clockwise direction as viewed in Fig. 2 with an anti-reversing device 19a preventing rotation of the drum in the opposite direction at any time while the dispenser is in operation.

As more particularly shown in the above mentioned application, the bottles and drum are stored in a refrigerated compartment 20 defined by insulated side walls 21, an insulated back door 22 which provides access for repair and maintenance and front closures including a narrow insulated front door 23 and an armored door 24. The drum is recharged with bottles when the armored door 24 and the insulating door 23 are opened. The armored door 24 covers and protects the coin control mechanism, this mechanism being thereby located outside of the refrigerated compartment where it can be readily serviced without wasting refrigeration and is free from the deleterious effects of cold and condensed moisture in the refrigerated compartment.

A handle 25 which is a part of the drive assembly B extends through a slot 26 in an embossed portion 27 upon the armored door where it is available for manipulation as by reciprocation through an arc of 120°. With this arrangement whenever the handle 25 is operated to drive the sprocket gear 18, movement in a clockwise direction takes the handle 25 to a position where it picks up the drive of the sprocket gear 18 and the back motion thereof rotates the sprocket gear 18 to index the drum as already described. The 120° movement of the handle 25 is enough to index the next stack of bottles into position and discharge the lower bottle thereof through the opening 13.

Coined controlled apparatus generally

In describing and claiming the invention the word coin is used in its generic sense because the invention is concerned with the number of coins deposited and not their authenticity. Therefore, the word coin as used herein includes tokens,

checks and other forms of medium of exchange, preferably made of metal or acceptable substitutes.

The coin controlled apparatus is located protectively behind the armored door 24 as indicated generally at 28 where it is disposed under a decorative panel 30. The coin receiving slots are indicated at 31 and the coin return receptacle at 32. The slots 31 and the receptacle 32 are preferably carried by the door and are provided with suitable tracks to transmit the coin to and from the coin control mechanism 28.

The coin controlled mechanism is mounted on the wall of the cabinet by brackets and bolts 33 which support side members 34 and 35 as identified in Figs. 2 and 3. The side members are in turn braced with tie brackets 37 and provided with vertically disposed grooves 36 affording tracks for receiving the coin detectors C and coin handling units D in supported cooperative relationship.

Although all the working parts of the coin control mechanism can be supported on both of the side members a third member 38 is employed for purposes of illustrating the invention to carry the strain of the transmission mechanism driving the sprocket gear 18. The supported elements, as will be seen in Fig. 2, are provided full access upon three sides for examination and servicing. Moreover, the anti-reversing device 19a on the drum prevents a reverse movement of the coin control mechanism as well as the drum, and the weight of the drum provides an inertia which retards the back movement of the handle 25 to serve more or less as a dash pot and thereby prevent an unduly fast operation of the mechanism.

The coin detector C is that part of the apparatus which safeguards the machine from the use of fraudulent coins or tokens in it. Although the detector shown relates to legal tender coins, same may be any one of a number of devices which utilize tokens or checks sold for use in the machine and for this reason the term coin detector is used in a generic sense to include all detectors which reject fraudulent coins or tokens.

Coin detector C

Except as used in the present invention for the purposes of automatic scavenging, the coin detector is of the usual construction, including a mounting plate 40 having flanges 41 received in the grooves 36 in the side members 34 and 35 to support the mounting plate 40 directly above the coin control mechanism D. Although the coin detector and coin control mechanism may be constructed as a single unit upon a single mounting plate, similar to 40, it is preferred for purposes of convenience and a better understanding of the invention that the two plates are separated from each other along the line 42 as viewed in Fig. 3.

The detector has a chute opening 43 at the top thereof which receives a coin deposited in one of the slots 31 and conducts the coin past a magnet 44 against a bouncing plate (not shown) which tests the coin for authenticity and passes it downwardly into the coin handling mechanism D if the coin is accepted. If the coin is not accepted, the magnet 44 either retains the coin against its face or the bouncing plate propels the coin into a coin return chute ending in receptacle 32 (Fig. 1). In view of the fact that the ferrous slugs will cling to the surface of the magnet 44, a scavenging lever 45 is pivotally mounted upon

the plate 40 as at 46 to drive a shaft which carries a suitable mechanism to open the sides of the chute 43 and wipe the face of the magnet 44 to clear the chute for the reception and handling of the next coin to be deposited.

It has been the conventional practice to actuate this scavenging operation manually and independently by separate manual control. In the present invention this scavenging is accomplished automatically whenever the price deposited in the mechanism is insufficient for any reason, whatsoever to actuate the article delivering mechanism. This automatic actuation of the scavenger is accomplished through a pull rod 41 which is releasably hooked to the lever 45 by a hook arrangement 48.

Coin handling unit D

The coin accepted by the detector drops into a chute 50 riveted to the back-side of the mounting plate 51 by rivets 52 as shown in Fig. 7. The chute 50 ends at 53 above a horizontally disposed plate 54 that is held in place by a bracket 55 and bolts 56. A slot 57 is provided immediately below the mouth 53 of the chute 50 through which a coin dropped in the chute will pass downwardly and into the control of a slide plate 58 spring-pressed for frictional engagement against the bottom of the mounting plate as by compression springs 60 disposed between a C washer 61 received in the slot on the end of bolts 62 which spring draws the head 63 against the bottom of the slide plate. The slide plate is movable between two alternate positions in one of which it prevents the coins from passing further and in the other of which a slot 59 in the slide plate registers with the slot 57 to permit free passage of the coin past the slide plate. Slots 64 are provided in the slide plate to allow for the slide motion. The slide plate 58 on the near side of the mounting plate 51 is provided with a supporting loop 65. This loop supports a push rod 66 which engages a pin 67 carried upon one arm of a lever 68 pivotally mounted at 70. Movement of the lever 68 about its mounting 70 cranks the drive arm 71 to which the pull rod 47 is mounted. The mounting in the embodiment shown is a releasable one in which a keyway 72 permits removal of the pull rod over a T-head 73 when the pull rod 47 is brought to a right angle to the position in which it is shown. Inward movement of the push rod 66 draws the pull rod 47 down to operate the scavenger of the coin detector C.

Upon the far side of the slide plate 58 is mounted a bracket 74 which carries a coin receptacle or well 75 registering with the slot 59. In the position shown in Figs. 7 and 8 the mouth of the coin well and the slot 59 are in register with the chute 50 so that a coin deposited in the chute 50 will drop into the coin well. However, if the slide plate 58 is slid to the left as viewed in Fig. 8 to its other position, the coin well 75 moves with it and the mouth thereto is carried out of register with the chute 50 so that any coins remaining in the chute 50 above those in the coin well are cut off so that the coins in the coin well can be discharged into the coin till of the dispenser.

To one side of the coin well, preferably directly above it, is mounted a bar 76 having transverse slots 77 therein to position a dog 78 with respect to the well in any one of a number of positions, the dog 78 being shown in the lowermost slot 77 in Fig. 7. The dog comprises two jaws urged by spring 80 to engage in the slot 77 and hook over

the far side thereof when released to the clamping action imposed upon them by the spring 80. The spring for the setting of the dog in any one of the slots 77 is depressed manually by pinching the ends 81 together.

Holes 82 are provided in the well 75 to receive the L-shaped end 83 on the dog 78 to provide a stop 84 for the coins whenever the well 75 is in the position shown. If either the well 75 or the dog 78 are moved away from the other, the stop 84 no longer supports the coins in the well 75 and the coins are free to roll out of the well 75.

The openings 82 and the slots 77 upon the rod 76 are spaced equal distances from each other 15, which distance is determined by the diameter of the coin or token expected to be deposited in the well 75.

Rotation of this rod 76 is accomplished with a push rod stamping 86 driven by the arm 71 of the lever 68. The push rod is mounted upon the mounting plate 51 by a pin and slot arrangement indicated generally at 87 and the upper end thereof is bent over to provide a flange 69 for the arm 71 to engage. The flange also provides a shoulder to receive one end of a torsion spring 88 which urges the push rod 86 to its upper position along with the arm 71. At its lower end the push rod 86 is bent outwardly to form a cam 90 which forces a follower 91 inwardly away from the observer as viewed in Fig. 7. The follower is carried by an arm on the rod 76, with the follower urged to engage the cam 90 by a tension spring 92 interconnecting one end of the arm and an anchor pin 93 on the mounting plate 51. Thus whenever the push rod 66 is forced inwardly, the arm 71 on the lever 68 forces the push rod 86 downwardly to drive the follower 91 inwardly. This rotates the rod 76 and carries the stop 84 from its resting position to release any coins present in the well 75. With this arrangement a complete scavenging of the entire coin handling mechanism is had whenever the push rod 66 is actuated.

Scavenger E and accepter F

Coins released from the well 75 by the dog 78 being moved permits the coins to move down the chute 85 and be returned to the return receptacle 32. When, however, the well 75 is moved 50 inwardly as carried by the slide plate 58, the lower end of the well 75 passes over a dividing edge 94 to discharge the coins into the coin till when the well 75 carries the coin therein beyond the control of the stop 84 and the dog 78.

As more particularly shown in Fig. 4 this back and forth movement of the well 75 is induced by a coin engaging or detecting means comprising an L-shaped lever 109 having a so-called hammer member or head 95. The hammer engages the 60 coin if it is there on its forward stroke and slides the well to the coin receiving side of the partition 94 while a back stroke stop 96 upon the bracket 74 is engaged by the hammer on the return stroke thereof to return the well to its initial position. An opening 97 is provided in the side of the well 75 nearest to the head 95 to permit the head to engage a coin occupying this station in the well.

In this way whenever reciprocation of the head 70 95 from its resting position as shown in Fig. 4 is had at a time when a coin is present at the station opposite thereto in the well 75, the well will be moved to the coin receiving side of the mechanism, and the coin will be discharged into the 75 coin till. Furthermore, whenever the well 75 is

moved to the coin accepting position by the head 95, the push rod 66 is also moved from its initial resting position. In event, however, a coin is lacking and reciprocation of the head 95 is had, movement of the head 95 is dissipated through the opening 97 without changing the position of the well 75 or the position of the push rod 66.

There being two heads 95 in the embodiment being described reciprocation of the heads 95 is had through a double cam slot 100 cut in a disc 10 member 99 keyed to the shaft 101 driven by the handle 25. A follower 102 carried at the elbow of a lever 103 mounted in fixed relationship at 104 and free at the other end 105 to drive a link 106, is employed to actuate the heads 95. In Fig. 4 the heads are shown in the position they assume when fully advanced with the coins present in both the wells 75 at that station, the handle 25 having been virtually advanced almost to its full position preparatory to its back movement. In this position the cam rise 107 has carried the lever 103 and the link 106 to their maximum advanced position. Each head 95 is carried by one end of an L-shaped lever 109 whose other end is pivoted as at 108 on a bracket 110 secured to the side frame 35. The elbow 111 of the lever is driven from the link 106 by a walking beam 112.

To the extent that the invention has been described thus far, only one coin handling mechanism has been described although several heads have been mentioned. One of the objects of the present invention is to provide a construction wherein coins of different denomination can be employed for the purchase price, such as a 5¢ piece and a penny if a 6¢ purchase price is desired for the machine. Other combinations of coins can be employed as will be presently seen, it being appreciated that the dog 78 can be adjusted up and down the bar 76 to any position which will permit a predetermined number of a particular coin to be deposited in the well 75. With the present invention more than one coin handling mechanism can be employed, two being shown in Figs. 1, 2, 3 and 4. The walking beam 112 shown in Fig. 4 operates two heads 95, either of which dissipate their energy through the opening 97 if no coin is present in their respective wells 75 at the appropriate stations. This expenditure of effort leaves the two wells 75 in their original position. Any coins present in the coin handling apparatus are ready for discharge upon the coin return side of the separator 94. This is also true if only one coin of the two required is present. The effort of the cam 107 is expended through the opening 97 in which there is no coin. On the other hand if there are coins present in the wells 75 where the heads 95 engage them, both wells 75 are moved to the coin receiving side of the separator 94. A slight relief 113 beyond the cam 107 releases the heads 95 from pressed contact with the coins so that the coins may be free to drop out of the respective well 75 past the now cleared stop 84.

With this arrangement in the use of the walking beam 112, the absence of a coin in the top-most position or station of either well 75, permits the effort of the cam to be expended without moving the well 75 from the coin return side of the partition 94 and it remains only to scavenge the coins from the coin mechanism by pushing the rod 66 to return the coins for insufficient funds. However, if coins are present in both wells where the heads 95 engage them, the purchase price is accepted by moving the well 75 inwardly and releasing the coins to drop into the 75 ber 138 bordering the slot, disposed under the

till. Once the coins are accepted, it only remains to discharge the article from the drum upon the back stroke of the handle 25.

A second cam is provided upon the disc 99 comprising an axial cam 119 on the bottom as viewed in Fig. 3 for axial movement of a follower 114 carried by one end of a lever 115 pivoted intermediate its ends as at 116 to the bracket 110. The other end 117 of the lever 115 operates a push rod 118 having a cam 120 at the top thereof. The push rod 118 is held in contact with the end 117 by a tension spring 121 and the push rod is supported for sliding movement by a slideway element 122 secured to the side frame 35 by screws 123.

The cam 120 engages a follower roller 124 mounted on one end of a lever 125 which is pivotally mounted as at 126 upon a bracket 127 fastened to the side frame 35 by bolts 128. The follower 124 operates two arms 130 to force the free ends 131 thereof inwardly along a predetermined path of movement, the arms 130 being held in a retracted position by a torsion spring 132.

The push rods 66 on the coin handling unit are in the path of movement of the ends 131 whenever the coin well 75 is in its resting position, namely, the position in which coins discharged therefrom would be returned to the purchaser in the receptacle 32. Thus whenever insufficient coins are present in either or both of the coin wells 75 of Fig. 4, movement of the cam 107 is expended by the heads 95 without moving the well 75 to the coin accepting position and the cams 107 and 119 are so timed that the ends 131 thereafter move into contact with the push rods 66 immediately following the full stroke of the cam 107.

In event, however, that coins are present in the wells 75 for the heads 95 to engage them, the heads will expend the effort of the cam 107 in moving the wells 75 to their coin accepting position and in this movement will carry the push rods 66 out of the path of movement of the ends 131.

Thus on the advanced stroke of the handle 25, the coin handling mechanism determines whether or not there is sufficient coin to make up the established purchase price, and, if there is, moves the coin well to a position accepting the coin. If there is not sufficient coins for the purchase price, the ends 131 contacting push rods 66 operate to scavenge the machine completely and return the coins present in the machine to the prospective purchaser.

Transmission G

A third cam 133 upon the disc 99 on the opposite side thereof from cam 119 operates a follower 137 which controls the action of a walking beam 134, one end of which operates a pull rod 135 and the other end a latch member 136. This actuation of the follower 137 takes place after the heads 95 have been moved to their advanced position by the cam 107, namely while the pin 102 (Fig. 4) is in the relief trailing the cam 107. A latch member 138 cooperates with the latch member 136 by means of a slot 140 in the member 138 through which the member 136 slides vertically. The slot is so formed that in one position of the member 138 the member 136 can slide freely downwardly and upwardly while in another position downward movement of the member 136 is blocked by a portion of the member 138 bordering the slot, disposed under the

chin of the member 136. The left-hand end of the member 138, as viewed in Fig. 3, projects beyond the side member 35 to a position adjacent the end of the slide plate 58. When the slide plate 58 is moved rearwardly it causes the member 138 to rotate through a small arc in a clockwise direction as viewed from above.

Immediately prior to the actuation of the follower 137 the other latch member 138 as shown in Fig. 3 is either carried by the slide plate 58 (Fig. 8) to a position blocking downward movement of the latch member 136 when the heads 95 move the wells 75 to coin receiving position or is left in its resting position permitting the latch member 136 to pass downwardly through the slot 140 therein whereby the action of the follower 137 is dissipated if the wells and slide plate 58 supporting them are not shifted to the coin receiving position.

This latching or non-latching of the two members 135 and 138 determines whether or not the pull rod 135 is actuated. If the members 135 and 138 latch with each other, as when the well 75 is pushed to its coin accepting position, the latching engagement serves as a pivotal support which cooperates with the follower 137 to drive the other end of the lever 134 downwardly to force the pull rod 135 downwardly. The upper end of the pull rod is secured to the outer end of an arm 139 which controls a yoke 141 of a clutch assembly which includes a triple toothed ratchet 149 and a carrier 143 supporting a pawl 144 normally held out of engagement with the ratchet by a collar 142. The carrier is rigidly carried by the shaft 19 while the ratchet 149 is journalled on the shaft 19.

The yoke spans the collar 142 and forces it downwardly whenever actuated by the arm 139 to provide space between the collar 142 and the pawl carrier 143. A pin 145 rigidly supports the pawl 144 as journalled in the pawl carrier 143 and at the lower end thereof has journalled thereon a follower 146 which drops into the space established between the collar 142 and pawl carrier 143 when the yoke 141 forces their separation on the forward stroke of the handle 25. A spring 150 urges the follower to enter the space thus provided.

The follower 146 holds the collar 142 down throughout the reverse movement of the handle 25 and releases a dog 156 rigidly secured to the pin 145 to permit a spring 157 freedom to urge the pawl 144 into engagement with the ratchet 149. This relation continues throughout the reverse movement until the follower 146 engages a suitable relief which permits the collar 142 to rise under the influence of a compression spring 147 held in place by the set screw collar 148 on the shaft 19.

Thus as the handle 25 approaches the end of its forward stroke the force of the cam 137 is expended to draw the yoke 141 downwardly if the proper purchase price has been deposited in the machine. By the time the forward stroke of the handle 25 is completed, the yoke 141 has retracted the sleeve 142 far enough for the follower 146 to drop inwardly under the influence of the tension spring 150 and release the pawl for engagement with the ratchet 149.

Whenever the pawl 144 is free to engage the ratchet, it will engage one of the three notches 151 provided for that purpose upon the ratchet as spaced 120° from each other. This engagement will occur with a self-correcting movement when the forward stroke of the handle is com-

pleted. Thereafter upon the back stroke of the handle 25, the pawl will force the sprocket gear 18 secured to the ratchet to turn and index the drum for the bottle on the bottom of the next advancing column to drop out through the delivery opening 13. When the back stroke is completed the sleeve 142 snaps upwardly and prevents the repetition of this action of the pawl 144 until the proper purchase price is again deposited in the machine.

Purchase price adjustment

The determination and checking of the proper purchase price is had by the setting of the dogs 78 in cooperation with the respective coin wells 75. If the dog is set in top position on both of two coin wells receiving nickels and pennies, respectively, the purchase price is determined to be 6¢; namely, one nickel and one penny. In event the desired purchase price is 7¢ the dog upon the penny well is dropped down to the second position to permit two pennies above it in the well. If the purchase price is 8¢, the penny dog is dropped another notch to permit three pennies to enter the well. This can be done also with nickels. Regardless of the number of coins to be deposited, the last coin making up the required number must be present at the station where the head 95 operates and in all instances the heads 95 determine whether or not the last coin is present in the well as indicative that all the other coins required for the purchase are also present in the well ahead of the coin checked.

Operation

When the proper purchase price is deposited in the dispenser the authenticity of the coins or tokens are determined by the coin detector and the coins deposited in the wells. When the wells are full, the machine is ready to make a delivery. The handle 25 is advanced from its resting position shown in Fig. 1 to the position where the cam 107 becomes effective. This cam drives the heads 95 against the top coins and moves the wells over to the coin receiving position after which the cam 119 comes into operation to drive the ends 131 of the levers 130 in the direction of the push rods 66. However, the push rods 66 by this time are out of the path of the movement of the ends 131 and the machine is free to accept the coins. Immediately thereafter the relief 113 releases the head 95 enough for the top coins to drop out and follow any other coins ahead of them into the till. In the meantime the latch members 136 and 138 have been brought into engaging position and the final forward movement of the handle 25 causes the lever 134 to be driven downwardly carrying the collar 142 down to let the pawl 144 engage one of the notches 151. Thereafter the return stroke of the handle 25 drives the sprocket gear 18 to index the drum to its next station at which station the lowermost bottle drops off of the drum and passes down and through the delivery opening 13.

In event, however, insufficient coins are deposited in the machine or an excess of coins is left in the machine following the preceding purchase without the excess being sufficient to constitute a proper purchase price, the movement of the heads 95 as driven by the cam 107 is expended in the slots 97 without affecting the position of the wells or the position of the push rods 66. Thereafter the cam 119 drives the follower 114 to move the ends 131 of the lever 130 into contact with the ends of the push rod 66. Further for-

ward movement of the handle 25 causes the ends 131 to push the rods 66 whereby the pull rod 47 scavenges the coin detector and the push rod 86 scavenges the coin handling unit of any coins present in or above the wells by rotating the dog 78 to carry the stop 84 out of the path of any coins present in the well.

It will be appreciated that suitable channels leading from the coin detector return will converge with the outlet of the return of the coin control mechanism and ultimately reach the return receptacle 32 shown in Fig. 1. The latch members 136 and 138, of course, remain in the position shown. The latch member 136 harmlessly expends the effort of the cam 133 and follower 137 by permitting it to move downwardly through the slot 140 unopposed by the member 138. As a consequence of this, the pawl 144 is held out of engagement with the notch 151 and the return stroke of the handle 25 accomplishes nothing.

This latter action of the coin handling mechanism on the forward stroke which is referred to herein as a scavenging action will repeat itself whenever the handle 25 is operated intentionally or playfully with insufficient coin present in the device to make a purchase. These keep all detectors wiped clean and the coin handling mechanism empty automatically.

Thus it will be seen that on the forward stroke of the handle 25 the question of the adequacy of consideration for the purchase is determined immediately and any coins deposited are returned if the funds are insufficient. In event, however, the coins are accepted on the forward stroke the article expected is delivered on the reverse stroke of the handle 25. The dispenser embodying the invention thereby more closely operates in a way characteristic of sales by hand delivery.

Full stroke mechanism

A full stroke mechanism in both directions may be provided for the handle 25, if desired, which assures that once the handle is started in its forward direction, a full stroke of the handle will have to be completed before it can be started back in the opposite direction and a full stroke mechanism is provided so that the handle once started in the opposite direction cannot be advanced again in the forward direction until full retraction of the handle is had. In this way there is no possibility of more than one article being delivered for a single purchase price or more than a single purchase price accepted with each article delivered. Such a full stroke mechanism is indicated above the disc 99 where a ratchet 152 having teeth 153 therein is engaged by a lock 154 operable for reverse action by means of the camming roller 155 pivotally mounted upon the ratchet 152. However, any suitable full stroke mechanism may be employed for movement of the handle 25 in both directions.

Coin handling unit D'

The function of the walking beam 112 can be incorporated in devices handling more than two denominations of coins. As shown in Fig. 9, the link 106 actuates a walking beam 160, one end of which checks the presence of pennies in the device and the other end of which detects the presence of quarters or a combination of nickels and dimes which is equivalent to a quarter through a second walking beam 161. Upward movement of the link 106 will exert its effort

in any one of three places; namely, through the one cent rod 162 and through the quarter rod 163 or the link 164 operable in turn to exert its portion of the energy through a leverage 165 and leverage 166 or leverage 167 which checks for the equivalent of a quarter.

The device as shown in Fig. 9 is set for a 27¢ purchase. The two pennies are present, the action of the link 106 causes the push rod 162 to force the pennies over to coin receiving position provided the other end of the walking beam 160 is supported also by suitable coin. If a 25¢ piece is present in the machine the push rod 163 will force the 25¢ coin well over to its coin accepting position and the purchase will be completed. However, in absence of a quarter, five nickels will be equivalent thereto in which case one end of the walking beam 161 determines whether or not the first nickel is present, and the lever piece 20 166 determines whether the fifth nickel is present. If both of these nickels are present, the nickel well carrying the five nickels is pushed to the coin receiving position, it being understood that the lever 165 is shown in the position opposing 166 only for purposes of understanding the operation of the device in the diagrammatical showing made of the relationship involved. In actual construction the two levers 165 and 166 will be moved in the same direction. However, 30 if only one nickel is present and two dimes, then the lever 167 will cooperate with the lever 165 to force the nickel and the dime wells over to coin receiving position.

Various combinations of these levers can be worked out when the principle is understood that each depends upon action of the other as a check upon whether or not all the coins required for the purchase price are present.

In any one of the embodiments shown and described herein, the dispenser can be set to operate upon a coin of a single denomination merely by blocking the action of the head 95 in which-ever coin handling mechanism a coin is not required. Under such circumstances the coin handle mechanism for that particular coin can be removed very quickly from the machine and without affecting its operation. On the contrary if the dispenser has been set to operate with one coin, it can be reset quickly for coin operation 45 involving two or more denominations by removing the stop holding the head 95 involved and dropping into the guideways the necessary coin detector and control mechanism necessary to handle the coins involved. The setting of the 50 dogs 78 on each mechanism determines the number of each coin required to operate the machine.

Having thus described the invention it will be readily apparent to those skilled in the art how the objects are accomplished and how various 60 and further modifications and changes can be made therein without departing from the spirit of the invention, the scope of which is commensurate with the appended claims.

What is claimed is:

1. In a device of the class described, a pair of fixed coin chutes, a slidable plate supported beneath said chutes and having two apertures therethrough for the passage of coins, resilient means for holding said plate in such position that 65 said apertures are in alignment with said chutes, a pair of coin receptacles each holding one or more coins, said coin receptacles being carried by said slidable plate and one receptacle being disposed beneath each of said chutes, a pivoted lever 70 element disposed at the top of each of said receptacles for exerting an upward force upon the 75 said slidable plate to move the same into a position in which the apertures are aligned with the said chutes.

tacles, one end of each element being disposed so as to project therein into coin engaging position when rotated in one direction and to be retracted from said position when rotated in the opposite direction, a beam pivotally attached to each of said elements at a point spaced from the coin engaging end thereof, a movable support for said beam, said beam being pivotally attached to said support at a point intermediate the points of attachment of said elements, cam means for advancing and retracting said support, said beam and elements being so arranged that if coins are present in the tops of said receptacles said elements will bear against same to move said plate out of alignment with said chutes when the support is advanced, and means controlled by said plate for dispensing an article each time said plate is moved out of alignment with said chutes.

2. In a device of the class described, a pair of fixed coin chutes, a slideable plate supported beneath said chutes and having two apertures therein for the passage of coins, resilient means for holding said plate in such position that said apertures are in alignment with said chutes, a pair of coin receptacles each holding one or more coins, said coin receptacles being carried by said slideable plate, one receptacle being disposed beneath each of said chutes, a pivoted lever disposed at the top of each of said receptacles, one end of each lever being disposed so as to project into said receptacle in coin engaging position when rotated in one direction and to be retracted from said position when rotated in the opposite direction, a beam pivotally attached to each of said levers at a point spaced from the coin engaging end thereof, a movable support for said beam, said beam being pivotally attached to said support at a point intermediate the points of attachment of said levers, manually actuated means for advancing and retracting said support, said beam and levers being so arranged that if coins are present in the tops of said receptacles the ends of said levers will bear against same to move said plate out of alignment with said chutes when the beam is advanced, and means for dispensing an article each time said plate is moved out of alignment with said chutes.

3. In a device of the class described, a pair of fixed coin chutes, a pair of movable coin wells each holding one or more coins disposed beneath said chutes, each of said coin wells being normally in a position in alignment with one of said chutes, means for urging said wells to said aligned position, a pivoted lever element disposed at the top of each of said wells, one end of each lever element being disposed so as to project therein into coin engaging position when rotated in one direction and to be retracted from said position when rotated in the opposite direction, a beam pivotally attached to each of said elements at a point spaced from the coin engaging end thereof, a mov-

able support for said beam, said beam being pivotally attached to said support at a point intermediate the points of attachment of said elements, manually actuated means for advancing and retracting said support, said beam and elements being so arranged that if coins are present in the tops of both of said wells said elements will bear against same to move said wells out of alignment with said chutes when the support is advanced.

4. In a device of the class described, the combination including a plurality of coin chutes, a plurality of movable coin receptacles normally positioned in alignment with said chutes and movable to a second position out of alignment therewith, coin receiving means disposed below said receptacles in alignment therewith when the receptacles are in the second position, stop means for determining the number of coins receivable in each of said receptacles and normally preventing the passage of coins out of said receptacles, said receptacles having stations occupied by said coins when a predetermined set of coins has been deposited, a pivoted lever for each of said stations, one end of each lever being disposed so as to project therein into coin engaging position when rotated in one direction and to be retracted when rotated in the opposite direction, a walking beam for rotating said levers, said beam being pivotally attached to each of said levers at a point spaced from the coin engaging end thereof, a movable support for said beam, said beam being pivotally attached to said support at a point intermediate the points of attachment of said levers, and manually actuated means for advancing and retracting said support, said levers bearing against coins in said stations to move said receptacles to said second position out of alignment with said coin chutes and away from said stop means when said support is advanced and all of said stations are filled.
